HIGH FREQUENCY OSCILLATOR

Horst Rothe and Hans Otto Roosenstein,
Berlin, Germany, assignors to Telefunken Ge-
sellschaft fur Drahtlose Telegraphie m. b. H.,
Berlin, Germany, a corporation of Germany

Application May 19, 1930, Serial No. 453,449,
and in Germany June 1, 1929

4 Claims. (Cl. 250—36)

It has been found that in the case of oscillator circuits for extremely high frequencies it is very difficult in practice to preclude radio frequency waves from the D. C. leads brought to

5 the apparatus. In order to obviate this difficulty the leads carrying plate and grid currents are suitably brought to a point in the oscillation circuit whose radio frequency potential to ground is as low as possible. In order that at the same 10 point the plate and the grid currents may be connected, one way out would be to insert in the circuit such a large blocking condenser C_b (Fig. 1) that the flow of radio frequency will practically not be influenced. However, especially 15 where very high frequencies are dealt with it is practically impossible in this scheme to pre-determine the point where the circuit is to be cut in such a manner that owing to the existent division of potential by way of C_{gk} and C_{ak} the 20 internal capacities of the tubes will present a minimum potential in the circuit. Once the cut or separation has been established, a change in location, i. e., a shift in tapping points for supplying D. C. potentials is but difficultly accom- 25 plishable.

In the accompanying drawing Figure 1 is given by way of explanation of the present invention described in detail in connection with Figure 2.

Now, according to this invention the incon- 30 venience already indicated, is obviated by that the oscillation circuit throughout its entire length is made to consist of two conductors 2, 4 (Fig. 2) presenting such a capacity in relation to each other that the entire system, looked at from 35 a viewpoint of radio frequency, may be conceived as a single conductor. One suitable embodiment consists in that the oscillating loop is built up of two or more copper bands or strips being sepa- 40 rated from one another by interposed layers of mica, for instance. Along these bands the taps 6, 8 for grid and plate current are effected by the aid of a double slide adjustable in the course of operations.

The arrangement here disclosed offers this fur- 45 ther merit that the two filament leads 10 con- jointly with the grid and the plate D. C. leads may be wound upon a choke-coil 14. The be- 50 ginning of the latter is connected by way of four blocking condensers K^1-K^4 to the shielding box 55 or cage of the set. This mode of grounding can be established again at another point of the choke-coil (K^5-K^8 , Fig. 2). It is recommend- able to so choose this second point that the two parts will exhibit practically no joint overtones. If proper care is taken in this respect it will be

possible to establish and provide perfect screen- 60 ing or shielding of the set which is otherwise but hard to insure in the case of ultra-short waves.

We claim as our invention:

1. A high frequency oscillatory circuit having, 60 in combination, an electron discharge device comprising an anode and a grid, an oscillatory circuit comprising two open ended, closely adjacent conductors, one of said conductors being connected with the grid, and the other of said con- 65 ductors with the anode, the open end of the con- ductor connected to the anode being near the connection point of the other open ended conductor to the grid, and the open end of the con- ductor connected to the grid being near the 70 end of the open ended conductor connected to the anode, said two conductors presenting such a high distributed capacity in relation to each other that they can be regarded as a single conductor from a radio frequency standpoint, a source of 75 grid potential and a source of anode potential, and leads extending from said sources to the open ended conductors connecting with said grid and anode, said leads being adjustable with respect to the ends of said conductors. 80

2. A high frequency oscillatory circuit having, 85 in combination, an electron discharge device comprising an anode, cathode and a grid, an oscillatory circuit comprising two open ended, closely adjacent conductors, one of said conductors be- 90 ing connected to said grid, and the other one of said conductors being connected to said anode, the open end of the conductor connected to said anode being near the connection point of the other open ended conductor to the grid, and the open end of the con- 95 ductor connected to the grid being near the end of the open ended conductor connected to the anode, a source of grid potential, a source of anode potential, and a source of cathode potential, leads extending from said sources of grid 100 and anode potential to the conductors connecting with said grid and anode, and leads extending from said cathode to said source of cathode potential, a choke coil, said supply leads for said cathode, anode and grid being wrapped upon said one choke coil and said choke coil being ground- 105 ed by way of condensers.

3. An oscillator having an anode a cathode and a control electrode, an open-ended conductor connected to said control electrode, an open-end- 105 ed conductor connected to said anode, said con- ductors lying adjacent each other and relatively parallel to each other, the open end of the con- ductor connected to said control electrode being adjacent the connection point of the open-ended 110

conductor connected to the anode, the open end of the conductor connected to said anode being adjacent the connection point of said open-ended conductor connected to said control electrode, a 5 source of anode potential, a source of control electrode potential, and adjustable means for coupling said sources through said open-ended conductors to said anode and control electrode at points intermediate the ends of said conductors, and individual condensers for said anode and control electrodes, the armatures on one side of said condensers being connected to said adjustable coupling means and the armatures on the other side of said condensers being in circuit with 10 said cathode.

15 4. Apparatus having, in combination, an electron discharge device comprising an anode, cathode and control electrode, an open-ended conductor connected to said control electrode, an 20 open-ended conductor connected to said anode, said conductors lying adjacent to each other and

relatively parallel to each other, the open end of the conductor connected to said control electrode being adjacent to the connection point of the open-ended conductor connected to the anode, the open end of the conductor connected to said anode being adjacent the connection point of said open-ended conductor connected to said control electrode, a source of anode potential, a source of control electrode potential, individual connections between said anode and control electrode sources of potential and points on said conductors intermediate their ends, said connections being adjustable on said conductors, a source of cathode potential connected to both legs of said cathode, individual condensers arranged between 25 said adjustable connections and ground, and additional condensers between both legs of said cathode and ground.
